(57) **CLAIM**

The ornamental design for container for food to be consumed on the move, as shown and described.

DESCRIPTION

FIG. 1 is a front view of a container for food to be consumed on the move, according to the present invention;

FIG. 2 is a left view thereof;

FIG. 3 is a back view thereof;

FIG. 4 is a right view thereof;

FIG. 5 is a top view thereof;

FIG. 6 is a bottom view thereof;

FIG. 7 is an axonometric view thereof; and,

FIG. 8 is an axonometric view thereof, shown in environmental use.

The broken lines shown represent unclaimed subject matter and form no part of the claimed design.
